UNITED STATES PATENT OFFICE.

WILLIAM S. HADAWAY, JR., OF NEW YORK, N. Y.

ELECTRIC IRON.

1,150,427.

Specification of Letters Patent. Patented Aug. 17, 1915.

Application filed September 5, 1911. Serial No. 647,693.

To all whom it may concern:

Be it known that I, WILLIAM S. HADAWAY, Jr., a citizen of the United States, residing at New York, in the county of New York and State of New York, have invented new and useful Improvements in Electric Irons, of which the following is a full, clear, concise, and exact description, reference being had to the accompanying drawing, forming a part of this specification.

My invention relates to electric heaters.

It is particularly applicable to electric irons, but it should be understood that it may be used in various other relations.

One of the objects of the invention is to provide an improved compact and efficient electric heater.

Another object is to provide a heater in which the heat is directly distributed to the surface to be heated in the proportions desired and with a minimum loss by radiation.

A further object is to provide a simple, inexpensive and rugged electric heater.

Other objects and advantages will herein-after appear.

The accompanying drawings illustrate an embodiment of the invention.

The views of the drawing are as follows:

Figure 1, shows a central longitudinal sectional view of one form of my invention. Fig. 2 shows a top plan view of the heating elements in position in the device. Fig. 3 shows a detail perspective view of one of the heating elements. Fig. 4 shows a detail perspective view of another heating element. Figs. 5 and 6 show details of construction.

I have illustrated my invention as applied to an electric laundry iron, having a bottom plate 1, upon which the heating elements 2 are carried. A thick heat insulating pad 3, preferably of asbestos is placed over the heating elements, as shown in Fig. 1, and is clamped down upon the same by a heavy ballast plate 4, adjustably attached to the bottom plate 1, as by suitable screws 5, having taps 6 and 7. An inclosing casing 8, is fitted over the retaining plate 4, and is held in position by the taps on the screws 5, which also serve to hold the shanks 9 of a suitable handle 10, in position upon the top of the casing. Suitable terminals 11, extend through the back of the casing 8 and are connected to the heating element 2.

In my improved construction the plate 1, which may be of any desired conformation, is preferably made of cold rolled steel,

punched out in one piece and drilled and tapped at points preferably along its center line to receive the screws 5. By the use of a punched piece of cold rolled steel I am able to avoid the necessity for machining any of the surfaces. On opposite sides of the upper surface of this plate 1, are fixed suitable longitudinally extending channels 12. In a preferred form, I electrically weld these channels to the plate 1. In the form illustrated in Fig. 2, the channels are made from stampings of metal which are provided with suitable slits in their sides, so that they may be bent into channel form. In the form shown these channels are so formed and arranged that their ends are somewhat closer together than their centers, since by this means I am able to distribute the heat more evenly to the sides of the iron. In the present form, the channels are carried on the plate 1, on opposite sides of the screws 5. If desired, one end of the channels may be cut away, to permit the passage of the forward screw, as shown in Fig. 2.

Within each of the channels 12, illustrated in perspective in Fig. 3, is placed a sheet of insulating material 13, conforming to the shape of the channel. Mica forms a suitable insulating material, but other insulating materials may be used if desired. Over the sheet 13, is placed a strip of resistance material 14 which may be of the well-known ribbon type. Over the resistance 14, is placed a second sheet of insulation 15, preferably of the same material as the sheet 13. Over the sheet 15, is placed a sheet of metal 16. After this sheet has been placed in position within the channel the sides of the channel are bent over, as shown in Fig. 3, so that the plate 16 is firmly pressed against the insulating layer 15, and the resistance material is tightly clamped in position. In the form shown, the strip of resistance material, the sheets of insulation and the upper sheet of metal are provided with rearwardly projecting extensions having perforations in their ends, adapted to receive the terminals 11. These ends are bent upward and forward, as shown in Fig. 3, so that they extend over recesses 17, formed in the back of the plate 4. In the present form, the end of the extension on the metal plate 16, extends beyond the terminals 11, and has its end turned slightly forward, so that it will rest flat upon the inner surface of the casing 8. The terminals 11, which may be

of any preferred type and for the purposes of illustration are depicted as of the plug type, extend through suitable perforations in the back of the casing 8. In the form 5 illustrated, the back of this casing is provided with a centrally located depressed portion 18, which slopes downward at an angle of substantially 30 degrees, as shown in Fig. 1. The depression is thus flanked by shoulders 19 at the corners. In the illustrated 10 form the perforations in this depressed portion are provided with suitable metal bushings 20, crimped to the edges of the perforations as at 21, and the terminals 11 are threaded as at 22 at their inner ends and 15 extend through the perforations in the ends of the bent up extensions 23, being secured to them by a suitable tap 24, and suitably insulated where necessary by washers 25 of 20 insulating material. If desired, the terminals 11, may be connected by a suitably insulated strip 25^a, which is preferably provided with suitable perforations in its ends, through which the terminals pass.

25 In the form of device illustrated, I provide the tip of the iron with a heating element of a different construction and arrangement from that just described. Said heating element is preferably inclosed with- 30 in a stamped metal casing, electrically welded to the plate 1 and having its sides 27 bent over upon the heating element as shown in Fig. 2. In this construction, however, the heating element is substantially triangular 35 in shape, and the sides of the metallic inclosing plate are bent over upon it entirely around its edges. As in the previous construction, I preferably place a sheet of insulating material 28, such as mica, upon the 40 bottom of the metallic casing. Over this sheet of insulation, however, instead of using the ribbon resistance I place a tape-wound unit, in which the wire is wound in substantially parallel convolutions, across the top 45 and bottom of a substantially triangular shaped sheet of insulating material 29, such as mica, as shown in Fig. 4, the different convolutions being spaced by stepped notches 30, preferably formed on the edges of the 50 sheet 29 which form the legs of the triangle. Over the resistance material a second sheet of insulation 31 is placed, which is preferably formed of the same material as the bottom sheet of insulation. Over this sheet of 55 insulation a metal plate 32 is placed, and after this sheet is placed in position the sides of the casing are bent down all around the unit, so that the resistance is firmly held in position. By preference I stamp out the 60 inclosing metal casing near one of its edges and at the back, as shown at 33, in Fig. 2, so that when the sides of the same are pressed down, an opening is left through which the ends of the resistance wire may 65 pass, so that it may be connected, as by spot-

welding, to the ribbon resistance carried on the body portion of the iron.

In the present form, the asbestos pad 3, is provided with a flange 34, on its lower surface which extends entirely around the units 70 and fits around the edges of the resistance units, so that when said pad is forced down upon the resistance units, these units are practically hermetically sealed between the same and the plate 1. I find that this heat 75 insulating pad may be made of a moderately dense grade of asbestos mill board. However, other materials may be used, if desired. The main function of the pad is to minimize upward radiation of heat to the ballast plate 80 4 whereby most of the heat developed is conducted readily through the steel plate on shoe 1 to the working surface. The ballast plate is not primarily a heat storage plate, but is used more to lend the necessary weight 85 to the device. In fact, said ballast plate, which is made preferably of cast iron, is not as good a conductor of heat as the steel shoe, and hence the latter absorbs the heat more rapidly than the former. For this 90 reason, the heat is conducted rapidly to the surface where it is needed, as fast as it is generated, and a heat storage plate is not needed. The use of a steel heating plate having the heating units integrally united 95 thereto results, therefore, not only in a more simplified structure mechanically, but in one having greater efficiency from a thermal standpoint. By the use of the heat insulating pad above described I am able to take 100 up all the irregularities of the surface of the resistance units and form a casing which fits tightly over the surface of these units. In the form illustrated, slots 35 are cut in the back of this sheet to permit the extensions 23 on the ribbon units to pass through the same.

The ballast or storage plate 4, may be formed of a rough casting without any machinery whatsoever, since any irregularities 110 in the surface of the plate are taken up by the insulating sheet 3. Thus it will be seen that a direct union is made between the heating units and the plate 4 by means of the insulating plate 3, and that any irregularities on the surfaces of either the units or the plate 4 may be overcome and in fact, turned to advantage by promoting a better union between the parts. The plate 4 is here shown as provided with recesses 36, on its upper surface to receive the screws 5, and it is also provided with the recesses 17, at its back, heretofore mentioned. The recesses 17 are spaced by a septum 37, and the plate 4 is made slightly shorter than the plate 3, 115 so that the extensions 23 on the ends of the ribbon units may pass up through the slots in the sheet 3, and be bent around the end of the plate 4, as shown in Fig. 1.

The casing 8, illustrated in section in Fig. 120

1, may be formed of any suitable thin material. By preference, it is formed or drawn from a thin sheet of cold rolled steel, and is so constructed that it incloses the plate 4 and the inner ends of the terminals 11. As illustrated in Fig. 1, this casing 8 rests upon the upper surface of the outer edge of the insulating sheet 3, so that it is insulated from the heating plate 4. This casing is spaced from the shanks of the handle 10 by suitable washers 38, which are preferably of an insulating material, so that the handle is insulated from the casing. It is of course obvious that when it is desired to use the heating device all that it is necessary to do is to connect a terminal plug to the terminals 11. The circuit then extends from one of these terminals through one of the ribbon resistance elements, through the tape resistance at the tip, and back through the other ribbon resistance to the other terminal. By my improved arrangement of resistance units and the employment of the two types of resistances in combination, I am able to properly distribute the energy input for the different parts of the iron in accordance with the area to be heated, and thereby secure uniformity of temperature. Further, by the use of the electrically-welded metallic casings or channels for the resistance units I am able to secure a very compact heater. Further, I am able to use a face plate of cold punched steel without the necessity of machining the surfaces of this plate and am thus able to cut down the cost of the manufacture. Further, I am able to use a rough iron casting, if desired, for the upper or ballast plate, and am able to do away with the necessity for machining the surfaces of this plate, the union between the parts being effectually made by the insulating sheet, which serves to equalize the pressure between the parts and at the same time serves to prevent the heat from being rapidly conducted upward away from the bottom plate. Further, by the use of the inclosing casing or shell I am able to inclose the parts in a suitable casing which rests upon the insulating plate and is thus insulated from the bottom or heating plate, so that the heat is not conveyed to the shell in such a manner as to be objectionable. By the use of the terminal bushings I am able to provide a dust-tight casing for the terminals. Further, by the use of the extensions on the resistance units, I am able to provide a stable support for the terminals.

While I have in this application, for the purposes of illustration, described one specific form which my invention may assume in practice, my invention may assume other forms and I consequently do not wish to be limited to the specific form herein described, but wish to cover all forms of the same

which fall within the scope of the appended claims.

What I claim as new and desire to secure by Letters Patent is as follows:—

1. In combination, an iron having a bottom plate, a flexible strip integrally united with said plate, a heating element held by said strip in intimate heat conducting relation with said plate, and means for confining to said plate the heat generated by said element. 70

2. In combination, an iron having a bottom plate of good heat conducting material, a flexible strip integrally united with said plate, a heating element held by said strip in intimate heat conducting relation with said plate, a heat insulating member covering said element to cut off the radiation of heat therefrom and a ballast plate to lend weight to said iron. 80

3. In combination, an iron having a steel bottom plate, a flexible strip integrally united with said plate, a heating element held by said strip in intimate heat conducting relation with said plate, a heat insulating member for confining to said plate the heat generated by said element, and means holding said member in intimate mechanical contact with the upper surface of said heating element. 90

4. In combination, an iron having a bottom plate, flexible strips integrally united with said plate and extending substantially around the edge of said plate, and a heating element held by said strips in intimate heat conducting relation with said plate. 100

5. In combination, an iron having a bottom plate, flexible strips extending along the edges of said plate, said strips being integrally united with said plate, intermediate strips integrally united with said plate, and means for heating said iron secured to and held in intimate heat conducting relation with said plate by said strips. 105

6. In combination, an iron having a bottom plate, flexible strips integrally united with said plate and extending from the rear thereof to the point and disposed adjacent to the edge thereof, flexible strips integrally united with said plate and located intermediate said strips, and means for heating said iron secured to said bottom plate by said strips. 110

7. In combination, an iron having a bottom plate, a plurality of substantially longitudinally disposed flexible strips integrally united with said plate, a plurality of triangularly arranged flexible strips integrally united with said plate and carried upon the end thereof, and means for heating said plate secured thereto by said flexible strips. 120

8. In combination, an iron having a bottom plate, a plurality of flexible strips integrally united with said plate and extending around the edge thereof, a plurality of 130

- flexible strips integrally united with said iron and intermediate said first mentioned strips, a flexible strip integrally united with said plate and extending transversely thereof, and means for heating said iron secured to and held in intimate heat conducting relation with said plate by said strips. 5
9. In combination, an iron having a bottom plate, a plurality of flexible strips integrally united therewith, a plurality of heating elements secured to said plate and held in intimate heat conducting relation therewith by said strips, a heat insulating gasket resting upon said heating elements, a ballast plate resting upon said gasket, and compressing the same upon said heating elements, and a casing inclosing said ballast plate and insulated from said bottom plate by said gasket. 10
10. In combination, an iron having a bottom plate, a plurality of flexible strips integrally united therewith, a heating element secured to said bottom plate by said ductile strips, said ductile strips having integral extensions, and terminal members secured to said extensions. 15
11. In combination, an iron having a bottom plate, a plurality of flexible strips integrally united with said plate, a heating element for said iron secured to said plate by said flexible strips, said heating element and said ductile strips having integral extensions, and terminal members secured to said extensions. 20
12. In combination, an iron having a bottom plate, a plurality of flexible strips integrally united therewith, a heating element held in intimate heat conducting relation
- with said plate by means of said strips, a ballast plate located above said heating element, terminal-carrying extensions integrally united with said flexible strips and overlying the end of said ballast plate, a casing inclosing said ballast plate and said extensions, and terminal posts secured to said extensions and extending through openings in said casing. 25
13. An electric iron having a shoe made of steel of substantial thickness whereby said shoe is rigid and capable of distributing heat over its acting surface, a flexible sheet metal carrier welded directly to said shoe whereby the thermal efficiency of the union between the carrier and the shoe is not impaired by expansion and contraction, a resistor arranged within said carrier and insulated therefrom, said carrier having flanges bent over said resistor for holding it in close thermal relation with said shoe. 30
14. In an electric iron, a metal shoe of good heat conductivity, an electric heater on the upper surface thereof, secured thereto in intimate heat conducting relation therewith, and a ballast plate above said heater, of less heat conductivity than said shoe, whereby the heat is conducted directly through said shoe to the work without being stored in said ballast plate to any substantial degree. 35

In witness whereof, I have hereunto subscribed my name in the presence of two witnesses.

Corrections in Letters Patent No. 1,150,427.

It is hereby certified that in Letters Patent No. 1,150,427, granted August 17, 1915, upon the application of William S. Hadaway, Jr., of New York, N. Y., for an improvement in "Electric Irons," errors appear in the printed specification requiring correction as follows: Page 2, line 68, after the reference-numeral "3" strike out the comma; page 3, line 9, for the reference-numeral "4" read 1, (numerical); page 4, line 15, claim 9, after the word "gasket" strike out the comma; same page, line 32, for the word "ductile" read *flexible*; and that the said Letters Patent should be read with these corrections therein that the same may conform to the record of the case in the Patent Office.

Signed and sealed this 7th day of September, A. D., 1915.

[SEAL.]

J. T. NEWTON,
Acting Commissioner of Patents.
